UNITED STATES PATENT OFFICE.

JAMES W. PHELPS, OF CHICAGO, ILLINOIS.

THERMODYNAMIC SWITCH.

Application filed July 14, 1920. Serial No. 396,128.

To all whom it may concern:

Be it known that I, JAMES W. PHELPS, a citizen of the United States, and a resident of Chicago, in the county of Cook and State 5 of Illinois, have invented certain new and useful Improvements in a Thermodynamic Switch, of which the following is a specification.

My invention relates to improvements in 10 electric thermo cutouts and thermo-dynamic elements therefor, and has special reference to such cutouts particularly adapted for flashing electric lamps and signs.

The object of my invention is to provide 15 a thermo-dynamic cutout which shall be simple and substantial in its construction; which shall operate positively to illuminate brightly and then dim an electric lamp; which shall have a thermo-dynamic element 20 which shall be capable of being manufactured rapidly and cheaply; and which can be constructed of bare or covered resistance wire.

One especial object of my invention is to 25 provide means whereby a relatively long resistance wire can be arranged in a small compass and whereby I am enabled to produce the required resistance with the use of a larger and lower resistance wire than 30 formerly and produce the thermo units at a less cost.

My invention resides in a covered thermal 35 element surrounded with a resistance coil produced in the novel manner herein described and arranged to short circuit the coil upon a pre-determined rise in temperature and to throw the coil into circuit upon a drop in temperature, thus upon a rise in temperature permitting the current to flow to light 40 the lamps connected with the device, and upon a drop in temperature placing the lamps and coil in series and thus dimming the lamps.

Furthermore my invention resides in the 45 method of producing a resistance element which consists in winding either a bare or a covered resistance wire around a core made of some good insulation substance such as asbestos, and then winding the core thus produced around a suitable support therefor, such as the expansion element of a thermo-dynamic switch.

If the resistance wire is bare it is wound 50 around the cord in spaced turns the cord being yielding enough and the wire wound tight enough to cause the wire to sink part

of or all of its diameter into the surface of the core and in winding such cord upon the support its turns are separated just sufficiently so that the wire on adjacent coils will not be short circuited. When insulated wire is used for the resistance wire it can be wound upon the core in turns which lie in contact and the turns of the prepared core on the support may be in contact without danger of short circuiting, but the element thus constructed is not so quick in its action as when bare wire is used. 60 65

I have illustrated several applications of this particular form of element, but this 70 invention has special reference to a cutout connection in the form of a combined plug and socket the element being arranged in the body of the connection between the end connections whether these connections are of 75 the screw threaded form shown, or other well known forms.

For a clear understanding of my invention 80 attention is directed to the accompanying drawings forming part of this specification, and in which:

Figure 1 is a fragmentary central longitudinal section of a thermo-dynamic cutout connection constructed in accordance with 85 my invention, showing a lamp in the socket end of the same;

Figure 2 is a longitudinal section of the thermo-dynamic element and its connections;

Figure 3 is a substantially central longitudinal section of the connection on the line 90 3-3 of Figure 1;

Figure 4 is a cross section of the connection on the line 4-4 of Figure 1;

Figure 5 is an electric circuit diagram;

Figure 6 is a perspective view of the insulation cord showing a bare insulation wire wound thereon; 95

Figure 7 is a similar view showing a covered wire wound on the cord;

Figure 8 is a plan view of a combined 100 screw socket block and a thermo-dynamic cutout;

Figure 9 is a vertical section on the line 9-9 of Figure 8;

Figure 10 is a plan view of a thermo- 105 dynamic cutout mounted on an insulation block and adapted to be interposed in a circuit; and

Figure 11 is a transverse section on the line 11-11 of Figure 10. 110

In said drawings, 1 is a thermo-dynamic element consisting of a curved bar or strap

2 of suitable metal such as nickel-chromium or nickel-copper, which has a high coefficient of expansion. The element is completed by a coil of resistance wire 3 wound 5 around the bar and insulated therefrom. The bar is held rigidly at its ends and is provided with a contact point 4 on its convex side at its middle portion, which is arranged to contact, as the bar expands, with 10 a fixed contact 5 and to be separated from said contact and break the circuit as the bar contracts.

This thermo element is, in the preferred form of connection, mounted in a suitable 15 opening 6 provided in a cylindrical shell-like body 7, which body carries at its ends suitable devices for readily inserting the device as a whole in an electric circuit. At one end I provide, as shown in Figures 1 20 and 3, a screw plug 8 by which the device can be connected in an ordinary screw socket for the supply of the current. At the opposite end I provide a screw socket 9 by means of which current can be readily taken off 25 as for the lamp 10.

The bar or strap 2 is rigidly mounted within and upon the body 7, which is preferably made of porcelain or some similar rigid insulation substance, by clamping 30 bolts 11 and 12 at its ends. The bolts pass through suitable openings in walls or shoulders 13 and 14 which are arranged beneath the ends only of the bar. The middle portion of the bar is curved away 35 from the plane of said shoulders and is free to take its shape as determined by its temperature.

The stationary contact 5 is carried by the inner end of an adjustable screw 15 which is 40 mounted in a suitable opening in the wall of the body 7 and is carried by a connecting plate or strap 16 secured within the opening 7 opposite to the element 2. This connector is secured rigidly to the body by screws 17. 45 The contact screw 15 is mounted in a screw threaded opening in the connector whereby it is adapted to be adjusted from and toward the element 2. The screw 15 is adapted to be held in the adjusted position by a compression spring 18 mounted between the head 50 of the screw and the plate 16, which thus applies friction to the screw and holds it rigidly in position.

The connecting strap 16 extends out into 55 the socket 9 and its end 16' is bent over to form the contact at the bottom of the socket with which the contact at the center of the base of the lamp connects. Just below the end 16' I provide an insulating washer 19 60 which is provided with an opening through which the end of the strap is passed before it is bent over and by which the washer is held in place.

At the opposite end of the device I provide 65 a connecting plate or strap 21 which has

its inner end clamped beneath the adjacent end of the bar 2 and the shoulder 14 by the clamping bolt 11 and its outer end 22 is projected through an opening 23 in a porcelain insulation plug or member 24 which 70 closes the body of the device at this end. The end 22 of the strap 21 is bent over upon the outer surface of the plug 24 to form the central contact at this end of the device. The threaded shell 8 forms the other contact, as is usual. The plug 24 is provided with a central projection 25 on its inner end which fits within a central opening in the screw plug shell 8 and is held central 75 thereby.

As an outer protector to the device I provide a cylindrical shell 26 made of fibre or some other suitable material adapted to slide over the socket 9 and the body of the device so that none of the screws or contacts are exposed. I provide the shell with an opening 27 in the side wall arranged immediately over the screw 15 so that this screw can be adjusted without removing the shell, to adjust the periodic flashing effect of the device. 90

To complete the return circuit I connect the two shells 8 and 9 by thin metallic connecting strips 28, preferably one arranged at each side, and which serve to tightly hold the said members in place on the body, the 95 ends of these strips being connected to the shells preferably by soldering.

As so far described and as illustrated in Figure 5, the current enters the device through the connector 21, passes to the bar 100 2 and when the circuit is complete at the contacts 4 and 5, through the screw 15 and strap connection 16 to the lamp 10 and returns through shell 9, and the connecting straps 28 to the shell 8 at the other end. 105

The resistance coil 3, which serves to heat the bar 2 and close the circuit at the contacts 4 and 5, is preferably made of resistance wire 29 which is wound on a flexible insulation cord 30, preferably made of asbestos or some similar non-inflammable material. When bare wire is used the turns 31 of the wire 29 are wound separated from each other to avoid short circuiting them and I retain them in such separated condition by winding the wire on the cord under sufficient tension to cause the wire to imbed itself either wholly or partly in the surface 110 of the cord.

In Figure 7 I have shown a resistance element in which I have used a resistance wire 32 which is covered by a winding 33 of cotton, silk or other suitable insulation material. In this form the turns 34 of the wire can be wound on the core 30, close together instead of separated. But I preferably wind the turns 34 slightly separated to permit the air to circulate around the wires so that the coil will cool promptly. 120

In Figures 8 and 9 I have shown another 125

application of the control element. In this instance a lamp socket 39 is mounted on a base 40 which is provided with two upstanding walls or projections 41 to which the 5 ends of the thermostatic element 2 are securely bolted. A third upstanding projection or wall 42 carries the connecting strip 43 which is bolted thereto by a fastening screw 44 and an adjustable contact 10 screw 45. The screw 45 is arranged opposite to the middle portion of the bar 2 similar to the screw 15 in the first form. One end of the connecting strip 43 is provided with a binding screw 46 for connecting a 15 lead wire 47 and the other lead is connected beneath a binding screw 48 which is mounted on the outer end of a connecting strip 49 which leads in to the center of the socket 39. The metallic shell 50 of the socket is connected to one end 51 of the bar 2 to which one 20 end of the resistance coil 3 is also connected. The opposite end of the coil 3 is joined to the connecting strip 43.

The operation in this instance is similar 25 to that already described, the current passes into the device through the connector 49, then through the lamp or whatever device is connected in the socket 39, then to one end of the bar 2. From this point it either 30 passes through the resistance coil to the connecting bar 43 and so out of the device, or it passes direct through the bar 2 to the bar 43. This passage of the current through 35 the resistance coil heats and expands the bar and closes the direct circuit through the bar 2 and the bar 43, thus shunting the resistance and causing the lamp to flash. The resistance wire being thus cut out it cools 40 off and soon the bar contracts and opens the direct circuit at the contacts 4 and 5.

In Figures 10 and 11 I have shown one 45 of the thermal elements mounted on an insulation base 52. The ends of the bar 2 are bolted firmly to the base and the center of the bar 2 is bowed up. Over the middle portion of the bar I provide a U-shaped bridge or support 53 to carry the adjusting screw 54 which carries at its end the contact 5. The construction and action of 50 the thermostatic element is exactly as in the former cases, viz, the expansion and contraction of the bar 2 serves to cut out and in the resistance coil 3 and consequently the

current flowing through the device varies from the maximum when the current is short 55 circuited, through the bar 2, to a minimum when it flows through the resistance coil 3.

In all forms of the device it is to be noted that the bar is bolted solidly to a rigid insulation base or element, that this 60 bar thus solidly mounted carries one of the contacts, that the other contact is also mounted on a part rigid with the base, that consequently vibrations will not affect the operation of the device. In consequence of 65 this the flashing of the lamp or lamps controlled by the device is positive and certain and it is substantially impossible for the device to either get out of order or to burn out, which frequently occurs with flashing devices 70 which have mechanically movable parts.

As many modifications of my invention will readily suggest themselves to one skilled in the art I do not limit or confine my invention to the specific structures or arrangements of parts herein shown and described. 75

I claim:

A flashing electric connection comprising a cylinder of insulating material provided 80 at one end with a screw socket and at the other end with a screw plug, a thermo electric switch within the cylinder comprising a metallic bar rigidly mounted at its ends and curved laterally between its ends, a 85 heating coil wound around said bar, one end of the coil connected to one end of the bar, a strap connection member clamped to said end of the bar and extended to form the center contact for said plug, a rigid metallic 90 bar opposed to said curved bar, an adjusting contact screw mounted in said rigid bar opposite to the middle portion of said curved bar for making and breaking connection therewith, the opposite end of said coil connected to said rigid bar, said rigid bar being extended at one end to form the center contact of said socket and metallic means connecting the shell of the socket with the shell of the plug. 95 100

Signed at Chicago, Ill., this 1st day of June, 1920.

JAMES W. PHELPS.

Witness:

T. D. BUTLER.
